METHOD OF APPLYING A PRESERVATIVE
TO EGGS

Herman B. Christian, Oakland, and Harry E. Kennedy, Berkeley, Calif.; said Christian assignor to said Kennedy

Application February 8, 1933, Serial No. 655,736

6 Claims. (Cl. 99—8)

This invention relates to a method and apparatus for applying oil or other preservative matter to eggs.

The method of processing or preserving eggs, which is now most commonly used, is that in which eggs are coated with a mineral oil either by submersion or precipitation, and then placed in cold storage.

This method is very efficient but is fairly costly due to the considerable quantity of oil consumed, the labor involved, and the breakage encountered; that is, the eggs must be carefully candled to be sure that all cracked, blood-spotted and defective eggs are removed. The eggs must be graded as to color and size. The eggs must be oil coated and then packed and placed in cold storage, and when removed from storage, must be unpacked and subjected to a sand blast to remove the oil coating, and then again re-packed before delivery to the trade.

The different operations or steps described require handling of the eggs over and over again. This increases the percentage of breakage and time and labor is proportionately increased with a considerable increase in final cost.

The chief function of the oil coating applied to eggs is to seal the pores against evaporation, and the effectiveness of a process may be measured by the loss of weight during a given period of time compared with eggs which have not been so treated. We have discovered that if eggs are subjected to a blast of mineral oil so finely atomized that the oil is like a fog, that the preserving action as measured by the above mentioned criterion is just as good, if not better, than that which may be obtained by simple immersion of the eggs. We have further discovered the distinct advantage, to-wit, that it is not necessary to remove the eggs from the fillers during the processing action but merely to spray the eggs from above and below, as while subjecting the eggs to the spray there is not sufficient oil deposited on the filler to be noticeable. The oil which is deposited on the filler renders it less hygroscopic so that during the period of storage the dehydration by filler material is greatly inhibited. We have also discovered that the film of oil, when deposited in this manner, is so infinitesimal that the undesirable gloss appearing on the eggs, when dipped or otherwise coated, is not apparent with the present method.

The object of the present invention is to generally improve and simplify the operation of processing or preserving eggs; to provide a method and apparatus for processing eggs whereby

handling and breakage of eggs is reduced to a minimum, oil consumption materially reduced, and sand blasting of the eggs to remove the excess oil after the eggs are taken from storage is entirely eliminated; and further, to provide a method and apparatus for applying a liquid preservative, such as oil or the like to eggs by projecting the liquid in a vaporous or atomized form against the eggs to seal the pores in the shells of the eggs.

The apparatus employed is shown by way of illustration in the accompanying drawings, in which—

Fig. 1 is a side elevation of the apparatus.

Fig. 2 is a plan view of Fig. 1.

Fig. 3 is a perspective view of one of the trays upon which the eggs are supported while the oil coating is being applied.

Fig. 4 is an enlarged cross section taken on line IV—IV of Fig. 1.

Fig. 5 is an enlarged longitudinal vertical section taken on line V—V of Fig. 2.

Fig. 6 is a perspective view of a standard form of egg crate.

Fig. 7 is a cross section of the egg crate showing it open to permit removal or insertion of the eggs.

Fig. 8 is a detail view in section showing the valve mechanism and the pipes connected with the atomizing nozzles.

Fig. 9 is a side elevation of Fig. 8, showing the manner in which the valve handle is actuated.

Fig. 10 is a sectional view showing a modified form of the apparatus.

Referring to the drawings in detail, and particularly Figs. 1 and 2, A indicates an elongated frame constructed of channel iron, or any other suitable material, the frame being supported by vertically disposed legs 2, or the like. Disposed at each end of the frame is a pair of cross shafts 3 and 4, these shafts being journaled in adjustable bearing members 5. Each shaft is provided with a pair of interspaced sprocket gears, indicated by dotted lines at 6, and these gears carry and support a pair of interspaced endless sprocket chains 7. These chains form a continuous belt, generally indicated at B, and this belt is continuously driven from an electric motor C through a reduction gear drive D and a belt or chain, as indicated at 8, said belt or chain driving the shaft 3.

The endless belt consists of the interspaced chain 7 and a plurality of plates or trays carried thereby, these trays being generally indicated at E. Each tray consists of a metal frame 9 con-

- structed of sheet iron or the like. The upper surface is covered with a wire mesh, as indicated at 10, and this forms a support for a layer of eggs and the filler in which they are supported.
- 5 The sides of the frame are channel-shaped, as shown in Fig. 3, and a bolt 11 passes through the center portion of each channel member, and is secured to a lug or similar device 13 carried by each chain. Each egg supporting plate is thus centrally supported with relation to the chains 1 and they are for this reason free to turn about the sprocket gears 6 as they pass around the same.
- 10 The eggs are placed on the trays at that end of the machine which is generally indicated at F, and they are removed from the machine at the opposite end or that indicated at G. The eggs in traveling from the receiving end to the discharge end first pass through a housing, generally indicated at H, where a coating of oil is applied, they then pass through a housing I where they are candled, and they are finally removed from the machine at the discharge end G, as will hereinafter be described.
- 15 The manner of applying the oil, or other preservative agent to the eggs, is accomplished as follows: Referring to Figs. 4, 5 and 8, it will be noted that a plurality of pipes 14 and 15 extend through the housing indicated at H. These pipes are placed above and below the conveyor whereby the trays are supported, and each set of pipes carries atomizing nozzles generally indicated at 16 and 17. The nozzles are identical in construction and the description of one will accordingly suffice. By referring to Fig. 8, a nozzle is shown at 16. This nozzle is in communication with a pipe 18 through which air under suitable pressure is supplied, the air being obtained from any pressure supply, such as a tank or the like, which is continuously charged by a pressure blower compressor or similar means. The air from the tank passes through a pipe 19 and on this pipe is mounted a valve 20. When the valve is opened the air passes through pipe 21 and this connects with the pipes 18 and the nozzle 16, hence giving a blast of air through the nozzle 16 whenever the valve 20 is opened. Extending through the pipe 18 is an oil supply pipe 22. This pipe connects with a nozzle 23 mounted within the nozzle 16. The flow of oil through the pipe 22 and the nozzle 23 is controlled by a valve 20a, and the oil is delivered to this valve through pipe 24, said pipe being connected with a source of oil supply under pressure or from a gravity tank as desired. The valves 20 and 20a are connected and are actuated by a common shaft 25 on the end of which is secured a valve operating lever 26. When the lever assumes the full line position shown in Fig. 9, both the air and oil valves are closed but when a tray loaded with eggs enters the housing a pin 27 secured either to the chain or the tray engages the valve handle, and when the handle is swung to the dotted line position indicated at 28, both valves will be opened and oil in a vaporous or highly atomized condition will be projected against the eggs both from above and below, and when the pin 27 reaches the dotted line position, indicated at 29, it releases the handle and the valve is immediately closed by a spring 30, or similar means. Thus, each tray carrying a layer of eggs is momentarily subjected to the atomized oil projected against the same and waste of oil is prevented, excess vapour being continuously removed through a pipe 31 which is connected with a suction blower or the like not shown.

Any vapour which condenses and runs down the side of the housing may be collected in a pan 32 and a drain pipe 33 connected therewith may remove the oil or return it to the source of supply if desired.

5 In actual operation the eggs to be processed are received in crates, such as shown in Figs. 6 and 7. The crates are placed on a table or conveyor J, arranged at one side of the machine at the point indicated at F. One or more operators standing at this point will remove the eggs layer by layer and place them on the trays as they slowly pass by. Each layer of eggs is permitted to remain in its filler. Both the filler and the eggs contained therein are placed on the trays, and as they pass through the housing H they are momentarily subjected to the oil applied in atomized or vaporous form, and they then pass out of the housing H into the housing I where they are candled by means of a light 48 placed below the conveyor, see Fig. 5. Defective or cracked eggs may here be removed, and when the eggs pass out of the candling housing they reach the discharge point indicated at G, where operators remove the fillers, together with the egg contained therein, and replace them in the egg crates; forks or similar implements being employed for this purpose so that a complete filler with the eggs contained therein may be removed in one operation. The crates, when re-filled, are placed in cold 30 storage and are there retained until they are to be placed on the market.

Where eggs are handled by the processing methods now in common use, it is necessary to first remove the eggs layer by layer from the crates and to place them in baskets or plates on a conveyor similar to that shown in this application, and then to remove the fillers as the eggs are either dipped or the oil is showered over the eggs as they pass through a housing similar to 40 that shown at H. The quantity of oil applied is very considerable, and in order that the coating shall not be too thick, it is customary to heat the oil to a fairly high temperature but, even so, the quantity of oil applied is excessive and the appearance of the eggs is undesirable as they have a glossy oily appearance. After the eggs have passed through this machine and have been coated, as described, the fillers must be replaced and the eggs are then removed, together with the 45 fillers, and placed in the crates. The crates are then placed in cold storage, and when they are removed from cold storage, they must again be unpacked as the oil coating must be removed before the eggs can be marketed. To accomplish 50 this the eggs are passed through a sand blasting machine, and in passing through this machine, the fillers are again removed and when they are passed through the machine the eggs will be replaced in the fillers, and the fillers, together with 55 the eggs, returned to the packing cases, and they are then ready for the market. This method requires handling and rehandling of the eggs over and over again. The breakage of eggs due to handling and re-handling increases in proportion. The quantity of oil consumed is also excessive.

By the present method re-handling of the eggs is reduced to the very minimum, and the eggs are at no time removed from the fillers, as it is only 70 necessary to remove each layer of eggs, together with their fillers, from the crates and place them on the trays of the machine shown in Figs. 1 and 2. After they are placed on the trays they pass through the housing H, where a blast of atomized 75

oil is projected against the eggs, both from above and below. This blast is momentary and the quantity of oil applied is so infinitesimally small that it does not detrimentally affect the appearance of the eggs, nor does it detrimentally affect the fillers in which the eggs are contained; conversely, it reduces moisture absorbing qualities of the fillers and to this extent reduces evaporation while the eggs are in storage. When the eggs have been oiled by the present method and replaced in the crates, they are put in cold storage, and when removed from cold storage may be marketed immediately as it is not necessary to remove the eggs and subject them to sand blasting, or other cleaning methods. Breakage due to handling and re-handling is, therefore, materially reduced and a considerable quantity of oil is saved.

In Figs. 1 to 9, a commercial or large size machine is illustrated such as would be employed in plants handling hundreds or thousands of cases of eggs a day. Where small quantities of eggs are handled, an apparatus such as disclosed in Fig. 10 may be desirable. This merely consists of a housing, such as indicated at 50, a shelf is formed in the housing, as indicated at 51, and a screen tray supporting the eggs to be oiled is pushed inwardly on the shelf. Spray nozzles, indicated at 54, are placed above and below the shelf, and a pair of valves to control the spray nozzles, similar to those shown in Fig. 8, are employed. A handle controlling the valves is placed adjacent the inner wall of the housing, or at one side thereof, and this is engaged by the tray when it is inserted. Hence, as the tray is inserted and shoved into place it engages the handle and the valves are opened, thus projecting a highly atomized or vaporous form of oil against the eggs, both from above and below, and by merely pulling the tray outwardly the valves are again automatically closed, thus completing the operation. Hence, a simple form of apparatus which functions in substantially the same manner as the larger form disclosed can be employed with equal efficiency. If cold weather is encountered and the oil is too viscous, it is obvious that it may be passed through a heater or the like.

Mineral oil has been described as the preservative agent, but it should be understood that any other liquid preservative capable of being atomized or converted into a vaporous form may be employed, and while certain features of the present invention are more or less specifically described, we wish it understood that various changes

may be resorted to within the scope of the appended claims. Similarly, that the materials and finish of the several parts employed may be such as the manufacturer may decide, or varying conditions or uses may demand.

Having thus described our invention, what we claim and desire to secure by Letters Patent is—

1. A method of preserving eggs which consists in creating a zone permeated with a highly atomized oil of foglike consistency, and exposing the eggs thereto for a period just sufficient to permit the atomized oil to seal the pores in the shells without leaving any perceptible coating of oil on the shells.

2. A method of preserving eggs which consists in producing by pressure applied to a liquid preservative, a vapor-laden area of fog-like consistency, and exposing the eggs thereto for a period sufficient to seal the pores in the shells without leaving a perceptible coating of preservative on the surfaces.

3. A method of preserving eggs which consists in creating a zone permeated with a highly atomized oil of foglike consistency and exposing the eggs, contained in the customary paper filler, thereto, for a period sufficient to seal the pores in the shells and to render the filler less hygroscopic.

4. A method of preserving eggs which consists in moving a plurality of eggs through a chamber filled with highly atomized oil of fog-like consistency and exposing the eggs thereto for a period just sufficient to seal the pores in the shells without leaving a perceptible coating of oil on the surfaces.

5. A method of preserving eggs which consists in creating within a chamber a zone permeated with highly atomized oil of fog-like consistency by projecting the oil under pressure from the top and the bottom thereof, and exposing the eggs thereto for a period sufficient to seal the pores in the shells without leaving a perceptible coating of oil on the surfaces.

6. A method of preserving eggs for cold storage which consists in creating a zone of foglike vapor formed by highly atomized liquid preservative, then passing the eggs contained in the customary paper filler through said zone, and timing the exposure of the eggs to the vapors so that the pores in the shells will be sealed without depositing any perceptible coating of the material upon the surfaces.
